DEVICE FOR THE AUTOMATIC CLEARING
OF THE REGISTERS OF COMPUTING MA-
CHINESAugust Kottmann, Sommerda, Germany, assignor
to Rheinische Metallwaren- und Maschinen-
Fabrik Sommerda Aktiengesellschaft, Som-
merda, Germany, a corporation of GermanyApplication July 16, 1931, Serial No. 551,224
In Germany July 29, 1930

8 Claims. (Cl. 235—75)

The invention relates to a device on completely automatic multiplying computing machines which is used when a relatively large number of multiplications are to be carried out with the machine in uninterrupted succession. The device, in accordance with the invention, when put into action, automatically sets the registers of the computing machine to zero before beginning each multiplication. Thereby on the one hand 5 the operator of the machine upon multiplying is relieved of the tedious setting to zero each time, and above all things the setting to zero of the registers cannot be inadvertently omitted, as long as the automatic zero setting device is in 10 action.

The device in accordance with the invention is to be used preferably in combination with calculating machines having an automatic multiplying device as described in French Patent No. 720,471, and a device for automatically returning the carriage as described in French Patent No. 721,550, wherein, aside from the main drive shaft of the computing machine, the clearing devices of the registers are also motor-driven, and consists of a mechanism which upon depressing the multiplication key first clutches the clearing device with the drive motor, but as soon as the clearing gears have been given the motion requisite for clearing the registers, interrupts the transmission of motion from the motor to the clearing gears and reconnects to the main drive of the computing machine.

The switching of the motion transmission from one shaft to the other can be accomplished either by a change clutch or by a differential driven by the motor whereby the shafts moving the clearing shaft and the main shaft can be selectively latched. Preferably, clutch devices are arranged between the clearing devices of the registers and the gears which move them, which make it possible to disconnect all or part of the clearing devices, so that in spite of movement of the clearing gears, in case of necessity, the clearing of the registers may be omitted.

An exemplary embodiment of the invention is illustrated in the drawings in combination with an electrically driven computing machine, in which the clearing gear is also motor-driven.

Figure 1 is a partly sectional diagrammatic plan view showing the electrical drive of the

computing machine and the device in accordance with the invention.

Figure 2 shows parts of the register mechanism and the clearing means, likewise in plan,

Figure 3 shows the motor key in side elevation, 5

Figure 4 shows the register and parts of the clearing means in front elevation,

Figure 5 is a plan view of the same, and

Figure 6 is a view of a three-element clutch and cooperating elements. 10

After the desired numerical values have been set into the machine, the motor key 1 is depressed, which moves the controlling bar 4 by means of the shaft 2 and the intermediate lever 3. The controlling bar 4 closes the electric circuit to the motor 7 by means of the contact device 6, and moves the clutch 5 (see German Patent 544,643, Figs. 5 and 6) into engagement so that the motor 7 will drive the bell-shaped housing 37 by means of the shaft 33, worm gear 20 drive 34, shaft 35, clutch 5, and shaft 36. The housing 37 carries with it the rotating bevel gears 38 of the differential drive mechanism. The bevel gears 38 mesh on one side with the bevel wheel 12, which is securely mounted to 25 rotate the shaft 23, and on the other side the bevel gears 38 mesh with a bevel wheel 39, which, together with the gear wheel 15 and the latch disc 14, forms a hollow shaft 32. The shaft 23 drives the main drive shaft 13 (Fig. 1) of the 30 computing machine by means of the gear wheels 24 and 25, and the bevel gears 26 and 27. The hollow shaft 32 rotates the cam disc 17 (Figs. 1 and 4) by means of gear wheels 15 and 16.

On the intermediate lever 8, which is rotatable 35 about a rod 8a fixed in the machine frame, there is pivoted on a pin 9b a pawl 9 held by a spring 9c against a stop pin 9a. The pawl 9 is thus rotatable clockwise about the pin 9b and can yield in this direction.

The extension 1a of the key lever of the motor key 1, when the key is depressed, by means of the pawl 9 and the intermediate lever 8 moves the latch slide 10, which cooperates with the latch disc 11 upon the shaft 23 and the latch 45 disc 14 of the hollow shaft 32 of the differential 12, driven by the motor.

By operating the motor key 1 the latch slide 10 is so shifted that its projecting edge 10a enters into a radial slot of the latch disc 11 and the 50

projection 10b leaves the radial slot of the latch disc 14. The latch disc 11 and the shaft 23 of differential gearing according to Patent No. 1,846,207 (Figs. 6, 7 and 8) are thus latched, 5 while on the contrary the latch disc 14 together with the gear wheel 15 are freed and are set into rotation by the differential 12. The gear wheel 15 meshes with the gear wheel 16 which is rigidly connected with the cam disc 17. Upon the edge 10 of the cam disc 17 runs the roller 18 of the angle ball 19 which is under-spring tension. Upon the first half revolution the cam disc 17 shifts the end 19a of the angle ball 19, in Figs. 1, 2 and 4, 15 to the right and thereby presses the slide 20 (Fig. 5), secured to the angle ball, against the clearing device 21, takes the latter along in the motion to the right, and in this manner provides the clearing of the results in the registers, because through the moving of the clearing means 20 21 to the right, rack bars 22 in known manner set the number rolls 28 to zero, are carried along. A resetting mechanism of this character is described and shown in U. S. Patent No. 1,797,699, dated March 24, 1931.

25 In the register carriage 42 illustrated in the drawings two registers are provided, which in general are both cleared together. The possibility exists, however, by shifting the slide 20 manually, of selectively clearing only one of the two 30 or even to completely eliminate the automatic clearing. The slide 20 (Figs. 1, 4 and 5) is so connected with the angle ball by means of a pin and slot arrangement 40 and 41 (Fig. 5) that the slide 20 is movable horizontally. In Fig. 5 the slide 20 35 is so arranged that the clearing levers 21 will not be carried therewith by the ball 19. If the slide 20 is moved toward the left, referring to Fig. 1, so that the projecting portion 20a of the slide 20 will meet the lower end 21a of the right hand 40 lever 21 of Fig. 5, then the projection 20b will also contact with the lower end 21b of the left-hand lever 21 of said figure. If the slide 20 is moved toward the left somewhat further so that the recessed portion 20c lies in the plane of oscillation of the ball 19 containing the lower end 21a 45 only the lever 21 lying toward the left will be carried along therewith. Notches are provided in the slide 20 to pass the clearing levers 21 freely upon moving through the angle ball 19, without 50 causing the latter to be carried along by the slide, and the clearing of the results therefore is also omitted.

If the clearing of the registers has been accomplished and the cam disc 17, gear wheel 16 and gear wheel 15 approach the completion of the first revolution, a bent portion 14a, provided upon the locking disc 14, will strike against the projection 10c of the locking slide 10 and will shift the locking slide 10 in such manner that the edge 10a of 55 the locking slide 10 is retracted from the radial slot of the locking disc 11, and the edge 10b of the slide enters the radial slot of the locking disc 14. The locking disc 10 and together therewith the entire motion transmitting elements for the 60 clearing device are therefore locked, but in place thereof the locking member 11 becomes freed so that now the rotations produced by the motor are transmitted through the differential, the shaft 23, gear wheels 24, 25, and bevel gears 26, 27, to 65 the main drive shaft 13, so that after completion of the clearing the calculating operation is carried out in known manner. The angle ball 19 is pushed back into its initial position by the clearing levers 21 which are under the tension of spring 31.

75 Summarizing:

Upon depressing the motor key 1 the motor 1 and the clutch 5 are engaged and simultaneously the main drive shaft 13 is latched, while on the contrary the shaft 15 driving the clearing elements is freed for the extent of one revolution. 5

After the clearing has been accomplished the clearing elements automatically become latched and automatically permit the transmission of motion from the motor to the main drive shaft 13.

In the arrangement according to Fig. 6 an alternative clutch 12' is used instead of the differential. The parts 10, 11, 12, 14, 15, 23, 32 of Fig. 1 correspond to the parts 10', 11', 12', 14', 15', 16', 23' and 32' of Fig. 6. The shaft 32' is a hollow shaft which is mounted freely rotatable upon 15 the shaft which is moved by the driving motor. The shaft 23' moves the main drive means of the calculating machine, the hollow shaft 32' drives the clearing means.

On depressing the multiplication key 1, the slide 20 10' is brought into the position illustrated in Fig. 6. The projection 10b' then shifts the central element 12' of the three element coupling mounted slidably but non-rotatably upon the shaft 36' driven by the motor, whereby it participates in 25 the rotation of said shaft 36'. The center element 12' is thus shifted into engagement with the second clutch element 32a connected to the shaft 32, whereby the shaft 32' and the gears 15', 16' and the eccentric 17, Fig. 4, are driven. 30

Upon depression of the multiplication key and shifting of the latching member 10', the edge 10a' of the latching member latches the shaft 23' along with the locking disc 11'. After a rotation of the shaft 32' the ramp 14a' of the latching disc 35 14' engages the edge 10c' of the slide 10' and shifts the latter to the left, Fig. 6, whereby the center element 12' of the clutch engages the third clutch element 32a' on the shaft 23'. Simultaneously the edge 10a' releases the latching disc 40 11' and the shaft 23', while the edge 10b' enters a radial slot 14a' of the latching disc 14' and thereby latches the said disc 14' and the shaft 45 32'. The shaft 23' then operates the main drive shaft of the calculating machine. 50

I claim as my invention:—

1. A computing machine comprising a completely automatic multiplying device; a motor; a main drive shaft for the computing mechanism; registers; a multiplication key controlling connection of the multiplying device to the registers; clearing mechanism for said registers comprising a drive shaft; transmission means alternatively effective to operate the main drive shaft and the clearing drive shaft by the motor; and means actuated by the multiplication key for controlling the transmission means to render said means effective to drive the clearing shaft, and means coming automatically into operation upon completed clearing of the registers to render said transmission means inoperative upon the clearing shaft and effective to drive the main drive shaft. 55

2. A computing machine comprising a completely automatic multiplying device; a motor; a main drive shaft for the computing mechanism; registers; a multiplication key controlling connection of the multiplying device to the registers; clearing mechanism for said registers comprising a drive shaft; a differential gear alternatively effective to operate the main drive shaft and the 60 clearing drive shaft by the motor; and latching means actuated by the multiplication key for conditioning the differential gear to drive only the clearing shaft, and means coming automatically into operation after the completed clearing of the 65 70 75 80 85 90 95

registers to render the differential gear inoperative upon the clearing shaft and conditioned to drive the main drive shaft.

3. A computing machine comprising a completely automatic multiplying device; a motor; a main drive shaft for the computing mechanism; registers; a multiplication key controlling connection of the multiplying device to the registers; clearing mechanism for said registers comprising 5 a drive shaft; a three element clutch comprising a central element driven by the motor and engageable alternatively with a second element connected to the clearing shaft and with a third element connected to the main drive shaft; means 10 actuated by the multiplication key for shifting the central clutch element into engagement with the second clutch element and out of engagement with the third element; and means operative upon completed clearing of the registers to shift the 15 central clutch element out of engagement with the second element and into engagement with the third element.

4. A computing machine comprising a motor, a main drive shaft; registers; clearing mechanism 20 for the registers; a multiplication key; means operated by said key for first applying the motor drive to the clearing mechanism; and means automatically effective on clearance of the registers 25 to shift the motor drive from the clearing mechanism to the main drive shaft.

5. A computing machine comprising a motor; a main drive shaft; registers; clearing mechanism for the registers; a multiplication key; a differential gear connected with the motor, the main 30 drive shaft, and the clearing mechanism; means for latching the drive connection of the differential gear with the main drive shaft and clearing mechanism; means operated by the multiplication key for unlatching the drive of the clearing mechanism.

anism for drive by the motor while latching that of the main drive shaft; and means for shifting the latching means at the end of a clearance of the registers to unlatch the drive of the main drive shaft for drive by the motor while latching 5 that of the clearing mechanism.

6. A machine according to claim 8 in which the motor driven shaft is connected to the zeroizing shaft and the calculating mechanism shaft through differential gearing having members co- 10 operating with the two transfer devices.

7. A machine according to claim 8 in which the motor driven shaft operates the zeroizing and the calculating mechanism shafts in alternation through a double coupling having an intermediate 15 element movable between two end elements to engage either of these shafts with the motor driven shaft while disengaging the other one therefrom.

8. An automatic multiplying machine comprising 20 a register, zeroizing means for the register, a shaft for driving the zeroizing means, a shaft for driving the calculating mechanism of the machine, a motor driven shaft, a motor key, connections actuated by the motor driven shaft and 25 capable of transmitting motion selectively to either one alone of said zeroizing and calculating shafts, control means for said connections movable between a first position in which the motor driven shaft drives the zeroizing shaft to a second 30 position in which the motor driven shaft drives the calculating shaft, means actuated by the motor key for bringing the control means from the second into the first position, and means actuated by the zeroizing shaft after it has driven 35 the zeroizing means through a complete zeroizing operation for returning the control means to the second position.

AUGUST KOTTMANN.
